No. 643,501.

Patented Feb. 13, 1900.

W. G. HOLMES & H. HOLLAND.

TROLLEY.

(Application filed Mar. 31, 1899.)

(No Model.)

UNITED STATES PATENT OFFICE.

WILLIAM G. HOLMES, OF ROSEVILLE, AND HENRY HOLLAND, OF DETROIT,
MICHIGAN.

TROLLEY.

SPECIFICATION forming part of Letters Patent No. 643,501, dated February 13, 1900.

Application filed March 31, 1899. Serial No. 711,240. (No model.)

To all whom it may concern:

Be it known that we, WILLIAM G. HOLMES, residing at Roseville, Macomb county, and HENRY HOLLAND, residing at Detroit, in the 5 county of Wayne, State of Michigan, citizens of the United States, have invented certain new and useful Improvements in Trolleys, of which the following is a specification, reference being had therein to the accompanying drawings.

The invention relates to construction of the trolley-stands for electric cars, especially designed for use on cars of considerable length, such as are used upon suburban lines. With 15 such cars the trolley-stand instead of being placed in the center of the car, as is usual with street-cars, must be placed nearer the rear end, so that the trolley may be controlled by the conductor from the rear platform of 20 the car. The objection to this is that when it is necessary for any reason to reverse the motion of the car the only way in which the trolley may be turned is by mounting the roof of the car, turning around the trolley-arm, and 25 engaging the trolley with the wire in the reverse position. This operation requires time and is also a source of danger to the operator, who is obliged to exercise great care to avoid coming into contact with the line-wire, wire accidents having frequently happened through 30 a slight slip or careless movement.

The present invention is especially designed to overcome this objection, and to this end consists in the construction of a trolley-stand 35 which is adapted to be shifted from a position at one end of the car to a corresponding position at the opposite end and may be moved from one position to the other by the operator without the necessity of his mounting the 40 roof of the car.

The invention further consists in the peculiar construction, arrangement, and combination of the various parts, all as more fully hereinafter described and shown.

45 In the drawings, Figure 1 is a side elevation of a car to which our improvement is applied. Fig. 2 is an enlarged cross-section through the movable carriage for supporting the trolley-stand and the rails on which said carriage 50 travels. Fig. 3 is a perspective view of a carriage detached and with the stand removed.

Fig. 4 is a longitudinal section through the carriage. Fig. 5 is an elevation of a portion of the carriage, showing the manner of locking the same at the end of the track.

55

A is the car, upon the roof of which is arranged a longitudinal track extending between the two positions at which the trolley-stand must be placed for the forward and rearward movements, respectively, of the car. 60 The track forms a runway and securing means for a traveling carriage B, upon which the trolley-stand is supported, and also preferably serves as an electric connection between the trolley and the motor-circuit on 65 the car. In the construction shown in the drawings this track is formed of the oppositely-arranged channel-rails C and C', with the grooves of which the wheels D of the carriage are adapted to engage. Each channel-rail is composed of two angle-bars a and b, secured together by the cross-bar c, the whole being mounted upon a suitable base or run board B' extending longitudinally of and secured to the roof of the car.

75

The carriage, as shown, comprises a plate E, extending across above the rails C and C' and provided with downwardly-projecting legs F, carrying the stub-axles G, upon which the wheels D are mounted. In order to insure 80 the easy running of the carriage, roller-bearings for said wheels are preferably used, as indicated at H.

Upon the plate E is mounted a pivoted plate I for supporting the trolley-stand. This plate 85 is preferably of diamond shape and is provided with antifriction-rolls J at its corners, which bear upon the plate E of the carriage. The pivotal connection is formed by a central pintle on the plate E engaging in a central 90 socket in the plate I. At each end of the carriage is arranged above the rolls J a segmental plate or track K, which serves to hold the plate I from being lifted from the plate E.

The trolley-stand proper is mounted upon 95 the pivotal plate I and may be of any suitable construction, but, as shown, comprises the head d, swiveled upon a pin or post L, secured to and projecting upward from the center of the plate I, and the socket e for the 100 trolley-arm is pivotally secured to said head d and provided with the segments f. The head

d is provided with a laterally-projecting arm *g*, to the outer end of which one end of a spring *h* is secured, the opposite end of said spring being attached to a flexible band passing over 5 said segment *f* and secured thereto, the arrangement being such that the tension of the spring *h* tends to draw the trolley-arm upward.

The trolley-stand being swiveled upon the 10 plate *I* may be turned thereon whenever the position of the trolley-arm is to be reversed; but the stand is normally held from turning on the plate by latches which hold it in one or the other of two positions. These latches 15 are preferably formed by the spring-arms *k*, attached at one end to the outer ends of the diamond-shaped plate *I* and extending inwardly therefrom. At their inner ends these arms are provided with oppositely-projecting 20 lateral arms having double inclines *l* and *m*, (shown in Figs. 2 and 3,) all so arranged that whenever the head *d* is turned upon its pivot the lateral arm *g* will engage with one of the inclines *m*, depressing the spring-arm *k* until the arm *g* passes over and engages with 25 the opposite incline *l*, when the tension of the spring-arm will force said arm *g* to a central position over the plate *I*.

The parts being constructed and arranged 30 as described, in operation the carriage and stand are located at one end of the track, as shown in full lines in Fig. 1, and in this position the trolley-arm extends backward to the rear end of the car. As the movement of 35 the car is forward when the stand is in this position there will be no tendency to move the carriage along the track. Whenever it is necessary to reverse the motion of the car, the operator disengages the trolley from the 40 wire and then by means of the guide-rope *N* draws the arm around into its reversed position, after which the carriage may be readily drawn along the track until it reaches the opposite end thereof and assumes the position 45 shown in dotted lines in Fig. 1. The lower rail of the track is preferably notched or cut away at each end at *O*, so that when the carriage is at either end of the track the end wheels will drop into the notches *O*, allowing 50 the plate *E* to drop down and rest upon the top rail of the track, so as to give a firmer support to the stand. When, however, the trolley-arm is reversed in position, the pull 55 on the rope *N* will tend to lift the wheels out of engagement with said notches *O*, so that the carriage may be freely drawn along the track.

It will be understood that when the trolley-arm is turned around the pivotal plate *I* will 60 first turn with it until the limit of movement of the roll *J* beneath the segmental track *K* is reached. The arm *g* will then disengage from the spring-latch arm *k* by sliding over the incline *l* and will then turn until it comes 65 into contact with and is forced over the incline *m* of the opposite latch-arm. At this point in the movement the trolley will be di-

rectly beneath the trolley-wire and can be engaged therewith, after which the tension of the latch-arm *k* will cause the incline *l* to turn 70 the plate *I* again into a central position over the plate *E*. Thus it will be seen that the stand is always held in one or the other of its two positions in relation to the plate *I*. The object of this plate *I* is to reduce the friction 75 in the swinging of the trolley-arm due to the passage of the car around curves or the lateral movement of the car in relation to the trolley-wire. It also serves to prevent the wear upon the pivot-pin. The first object is 80 accomplished by the antifriction-rolls, which, being placed a considerable distance from the center of the stand at each end, (by reason of the elongated or diamond shape of the plate *I*,) will bear down with less pressure 85 on the plate *E* than if close to the center of turning. The second object is attained by the upper plate or tracks *K*, which hold down the rear end of the plate *I*, and thus take away 90 all strain from the pivot due to the springs *h*, the pressure being borne by the rolls *J* and the plates.

Another advantage of the traveling trolley-stand is that when it is necessary to back the car for but a short distance, as in turning the 95 car around on a Y-track, this may be done without reversing the trolley, and should the latter by any chance run off the wire and become fouled with the cross supporting-wires 100 the travel of the carriage along the track will prevent the tearing down of the overhead structure until the car can be brought to a stand.

What we claim as our invention is—

1. The combination with a car-roof, of a 105 trolley-stand secured to, and mounted for longitudinal travel upon said roof between two positions on opposite sides of the longitudinal center thereof, and a trolley-arm rotatably mounted upon said stand.

2. The combination of a trolley-stand and a track extending longitudinally of the car, to which said stand is secured and over which it is adapted to travel from a position at one end thereof to a corresponding position at the 115 opposite end.

3. The combination with a car-roof, having a track extending longitudinally thereof, of a carriage secured for travel along said track and a trolley-stand rotatively mounted on said carriage.

4. The combination with a car-roof having a track extending longitudinally thereof, of a carriage secured for travel along said track, a pivotal plate secured to said carriage and a trolley-stand, mounted upon said pivotal plate and adapted to be rotatively adjusted into two positions thereon.

5. A trolley-support comprising a base-plate, a plate, having the trolley-stand mounted thereon, said plate being pivoted to said base and having antifriction-rolls at its forward and rear ends, and segmental tracks upon said base respectively below and above

said forward and rear antifriction-rolls for the purpose described.

6. A trolley-support comprising a base, a pivotal plate having a limited rotative movement upon said base, a trolley-stand swiveled upon said plate having a laterally-extending arm and the spring-latches *k* upon opposite sides of said plate having the lateral arms provided with the opposite inclines *l* and *m* for the purpose described.

7. A trolley-support comprising a base, a plate centrally pivoted to said base provided with roller-bearings at its outer ends adapted to have a limited travel on said base, a head carrying the trolley-arm socket, and springs

pivoted to said plate and means for locking said head to said pivotal plate in two opposite positions thereon.

In testimony whereof we affix our signatures in presence of witnesses.
